UNITED STATES PATENT OFFICE.

DAVID S. KENNEDY, OF BROOKLYN, NEW YORK, ASSIGNOR TO MERGENTHALER LINOTYPE COMPANY, A CORPORATION OF NEW YORK.

SPACE BAND FOR LINOTYPE MACHINES.

Application filed December 13, 1927. Serial No. 239,628.

This invention relates to justifying spacers or spacebands such as those used in the commercial linotype machines for the justification of a matrix line preparatory to the casting operation. Ordinarily each spaceband comprises a short wedge-shaped member formed with projecting ears to adapt it for circulation through the machine and to lock in the composed line during justification, and 5 a longer wedge-shaped member carried by the first or shorter member and slidably connected thereto in such manner that it (the longer member) may be thrust upward through the composed line to expand or elongate the same in effecting the justification.

The standard spacebands, in their normal or extended condition, are substantially four and one-quarter inches long and circulate in such condition, this dimension bearing a fixed 20 relation to certain parts of the machine. They are also produced in several different thicknesses, ranging approximately from a minimum of thirty-two thousandths of an inch to fifty-two thousandths at the sliding 25 point when unexpanded, so as to afford the proper spacing for various classes of printed matter. There are certain classes of work, however, wherein the required word spacing is so slight that even the thinnest spacebands 30 are much too thick to be used. In such cases, it has heretofore been necessary to resort to what is known as "solid spacing", that is to say, to the use of non-expandable blank matrices or spaces of the requisite thinness. In 35 most instances, these "blank spaces" are carried as "pi" and must be composed in line entirely by hand. This old practice requires extreme care and skill in justifying the individual lines, and moreover is extremely slow, 40 tedious, and expensive.

The present invention is intended to overcome these and other difficulties, and contemplates a spaceband of the regular expandable variety but which is much thinner than heretofore and which, at the same time, is capable of withstanding the strains of justification without bending or breaking. A characteristic feature of the improved spaceband is that it is substantially shorter than the 50 standard spaceband and for this reason may be made proportionately thinner while still possessing the required strength and rigidity. In the preferred embodiment illustrated, the short stationary wedge-shaped member of the improved spaceband is of

standard length and form, but the relatively movable wedge-shape member is approximately one-half shorter than the corresponding member of the standard spaceband, such one-half reduction in length of the movable 60 member being found to answer the requirements very satisfactorily.

The invention also includes certain improvements in different elements of the machine intended to provide for the handling 65 and operation of the improved spacebands. These will be more clearly understood from the detailed description to follow.

Referring to the drawings:

Fig. 1 is a front view of a portion of a linotype machine showing the application of the 70 present invention;

Fig. 2 is an enlarged side elevation, partly broken away, of the spacer magazine equipped for handling the improved spacebands; 75

Fig. 3 is a transverse section take on the line 3—3 of Fig. 2;

Figs. 4 and 5, are, respectively, side and edge views of the improved and the standard spacebands, giving a comparison of the 80 two;

Fig. 6 is an enlarged cross section of the improved spaceband taken on the line 6—6 of Fig. 4; and 85

Fig. 7 is a detail transverse section through the justifier showing the spacing block detachably secured thereto.

Referring to Fig. 1, the matrices and spacers are released from their respective storage 90 magazines A, B, by the operation of the keyboard C and are delivered, one by one, to the assembler D wherein they are composed in line. The assembler is then raised and the composed line transferred horizontally 95 through the intermediate channel E to the dotted line position 1 where it is received by the first elevator F, which immediately descends to present the line in the casting position 2 between the confining jaws G, G', the latter serving to sustain the line endwise as 100 the spacebands are thrust upwardly therethrough by the justification slide H. After the line is justified and the cast is made, the first elevator lifts the matrices and spacebands to the dotted position 3 from which 105 they are shifted to the upper transfer channel for separation and subsequently returned to their storage magazines A and B, respectively. 110

As shown in Fig. 4, the improved spaceband comprises two oppositely tapered or wedge-shaped members J, J', whose outer faces are vertical and whose inner engaging faces are inclined at the same angle so that the outer faces will remain parallel at all times. The shorter member J is the stationary part, being provided at its upper end with supporting ears j which hold it against movement during justification; while the longer member J' is the movable part, being slidably connected to the member J in such manner as to be shoved upwardly through a composed line in effecting the justification thereof. Although the present improvements are equally applicable to other types of spacebands, they are herewith illustrated as applied to the particular type of spaceband disclosed in the patent to Beck, No. 1,424,870. As more fully disclosed in said patent, the movable member J' is formed so as to present two marginal bars j' and a centrally located bar j². The latter bar is beveled on its opposite edges to engage a pair of undercut guides j³ formed on the inner inclined face of the stationary member J, and the sliding joint or connection thus provided serves to hold the said members in proper contacting relation while permitting the member J' to be moved relatively to the member J in expanding and contracting the band as a whole. At their upper ends, the bars j', j², of the member J' merge into a thin connecting web j⁴ and, at their lower ends, are connected together by a longer and much thicker web portion j⁵.

The standard spaceband is illustrated in Fig. 5, and by comparing it with the improved spaceband shown in Fig. 4, it will be seen that the two differ only in respect to length and thickness. The short stationary sections J are practically of the same length in both cases, but the movable sections J' differ substantially in length, the section J' of the improved spaceband being approximately one-half as long as the section J' of the standard spaceband, thus making the over-all length of the improved spaceband about two-thirds that of the standard spaceband. It is on account of this difference in length between them that the improved spaceband can be and is made proportionately thinner, as shown, it now being apparent that the shortening of the movable section J' of the improved spaceband permits it to be thinned down to whatever extent it is shortened without destroying the inclination of the wedge surfaces. Notwithstanding its extreme thinness, the movable section of the improved spaceband, by reason also of its reduced length, will possess ample strength and rigidity to resist bending or breakage when thrust upwardly through the line. In other words the shortening of the movable section brings its lower end, where the expanding

force is applied, correspondingly closer to the lower end of the stationary section, where resistance to the expanding force or the lateral pressure created thereby occurs. This matter of rigidity of the movable section is important, as the force applied thereto in effecting the justification of a composed line is quite considerable, amounting to as much as seventy (70) pounds or so. It can be seen therefore that the problem solved by this invention could not be met simply by thinning down the two cooperating wedge-shaped members of the standard spaceband, even if the thickness of the standard parts were great enough to allow this to be done. 70 75 80

In carrying out the invention, certain changes have also been made in the storage magazine B and the justification slide H in order to cooperate with the improved spacebands. 85

As ordinarily constructed (see Fig. 2), the magazine B is provided with a pair of inclined rails B' from which the spacebands are suspended by their projecting ears j. In the case of standard spacebands, the leading one in the magazine is arrested at its upper end in operative relation to vertically disposed escapement fingers B² by shoulders B³ formed on the rails B', and it is supported at its lower end by the upper edge of the chute plate B⁴ which is curved inwardly and arranged so that the band will stand at an inclination with its upper end foremost, as indicated by the dotted lines. The release of the band is effected in the usual way from the keyboard C through a lever B⁵ and the rocking arms B⁶, the latter being pivotally connected to the respective escapement fingers B². Thus, as the arms B⁶ are rocked upwardly, the fingers engage the ears of the leading spaceband and lift it over the shoulders B³, allowing the lower end of the band to swing by gravity clear of the plate B⁴ to a position over the chute. At the same time, the ears ride over the top of the shoulders B³ and the band drops through the chute to the assembler. 90 95 100 105 110

Inasmuch as the improved spacebands are much shorter than the standard bands, they would fail to engage the arresting plate B⁴ and hence would swing forwardly upon their ears to a vertical position within the magazine and so be incapable of cooperating properly with the escapement fingers B². Additional means are therefore provided for arresting these shorter spacebands at the required inclination. Such means, in the present instance, comprise (Figs. 2 and 3) a pin K which extends across the magazine from one side to the other and is arranged in position to engage the lower ends of the improved bands as they slide down the rails B'. As best shown in Fig. 3, the crosspin K is provided with a screwhead K' and a threaded portion K², which latter screws into 115 120 125 130

a hole tapped in the back plate of the magazine, thus enabling the pin to be readily applied or detached as desired. Since the short bands may be used only on special occasions 5 when setting certain classes of work, it is advisable to provide in some such way for a quick conversion of the magazine to handle either the improved or the standard spacebands.

10. In the use of the standard spacebands, the movable sections J' are driving up through the composed line by direct contact with the customary justification bar H', which has a range of movement controlled 15 by an operating cam on the main shaft of the machine, all as well understood. In order that the standard parts may be utilized to operate the shorter sections J' of the improved spacebands, the justification bar H' 20 is provided with a building-up block or pad L, which increases the height of the justification bar sufficiently to compensate for the reduced length of the movable sections. As preferred the pad L is detachably connected 25 to the justification bar, as by means of screws L', so that it may be applied or removed at will according as the machine is equipped with the improved or the standard spacebands. In this way the regular operating 30 cam may be employed without change to cooperate with spacebands of one kind or the other as desired.

Having thus described my invention, its construction and mode of operation, what 35 I claim and desire to secure by Letters Patent of the United States, is as follows:

1. In a linotype machine, a spacer magazine for handling spacebands of two lengths, one to the exclusion of the other, comprising 40 an escapement device for releasing the spacebands one at a time, a stop for arresting spacebands of standard length in operative relation thereto, and auxiliary means movable into or out of operative position, for 45 arresting spacebands of substantially less than standard length in operative relation to said escapement device.

2. In or for a linotype machine, a justifying spaceband of less than standard thickness 50 and comprising a relatively stationary wedge-shaped member and a movable cooperating wedge-shaped member slidably connected thereto, said movable member being of sub-

stantially less than standard length to give 55 it the required strength and rigidity.

3. In or for a linotype machine, a justifying spaceband of less than standard thickness and comprising a relatively stationary wedge-shaped member of substantially standard length and a movable cooperating wedge-shaped member slidably connected thereto, 60 said movable member being approximately one-half of standard length to give it the required strength and rigidity.

4. In a linotype machine, the combination 65 of a series of circulating spacebands of substantially less than standard length, a standard pusher or justifier, and a spacing block detachably secured thereto to compensate for the reduced length of the spacebands, said 70 block being removable at will to adapt the pusher to spacebands of standard length.

5. In a linotype machine, the combination 75 of a series of circulating spacebands of substantially less than standard length, a standard magazine wherein said spacebands are stored and equipped with an escapement device arranged to cooperate with the upper ends of the spacebands, and a stop associated with the magazine for arresting the spacebands at their lower ends in operative relation to the escapement device, said stop being removable at will to adapt the magazine 80 to handle spacebands of standard length.

6. In a linotype machine, the combination 85 of a series of circulating spacebands of substantially less than standard length, a standard magazine wherein said spacebands are stored and equipped with an escapement device arranged to cooperate with the upper 90 ends of the spacebands, means associated with the magazine for arresting the spacebands at their lower ends in operative relation to said device, said means being removable at will to adapt the magazine to handle spacebands of standard length, a standard pusher or justifier, and a spacing block detachably connected thereto for increasing the height 95 of the justifier to compensate for the reduced length of the spacebands, said spacing block likewise being removable at will to adapt the pusher to spacebands of standard length.

In testimony whereof, I have affixed my signature hereto.

DAVID S. KENNEDY.
